DESIGN FOR AN ELECTRIC IRON

Allan E. Ross, Vancouver, British Columbia,
CanadaApplication August 12, 1947, Serial No. 140,832
In Canada May 3, 1947

Term of patent 14 years

(Cl. D49—6)

To all whom it may concern:

Be it known that I, Allan E. Ross, a subject of the King of Great Britain and a resident of the city of Vancouver, in the Province of British Columbia, Canada, have invented a new, original, and ornamental Design for an Electric Iron, of which the following is a specification, reference being had to the accompanying drawing, forming part thereof, wherein the figure is a perspective view of an electric iron, showing my new design, the opposite side showing substantially the same appearance as the side shown.

What I claim:

The ornamental design for an electric iron, as shown and described.

ALLAN E. ROSS.
